COUCH BED

Gustave A. Johnson, Weymouth, Mass., assignor
to New England Bedding Company, Medford,
Mass., a corporation of Massachusetts

Application December 7, 1935, Serial No. 53,394

1 Claim. (Cl. 5-18)

This invention relates to couch beds of the extensible type and its principal objects are to provide a couch bed having a back-rest, a stationary section and a movable section which may be conveniently drawn to extended position either to form twin beds or a double bed accessible from either side without removing the back-rest or any of the parts, and to provide a couch bed which is of simple and economical construction having but few parts, which is efficient in operation and durable in use, and which can be manufactured and sold at a relatively low cost.

Further objects relate to various features of construction and will be apparent from a consideration of the following description and accompanying drawing, wherein:

Fig. 1 is a front elevation of a couch bed constructed in accordance with the present invention;

Fig. 2 is an end elevation showing the sections in nested position;

Fig. 3 is a fragmentary end elevation showing the movable section in extended position; and

Fig. 4 is a section on the line 4-4 of Fig. 3.

The particular embodiment chosen for the purpose of illustration comprises a main or movable section and a stationary section, designated generally by the numerals 1 and 2, respectively, both of which sections may be of the general construction shown in my copending application Serial No. 652,159, filed January 17, 1933.

The main section comprises a box-like structure having a front wall 4 and side walls 5 and 6, the rear being open so that the main section may be drawn from about the stationary section. The top of the main section may be of the usual construction for supporting a pair of mattresses 9 which provide the seat cushion when the structure is used as a couch. The outer faces of the front and side walls may be provided with a suitable finish, such as textile fabric, which may be secured to the lower mattress so as to hold it in position and give the appearance of continuity therewith. The ends of the side wall are provided with vertically extending angle irons 10 whose lower ends are provided with casters or rollers 11 which support the main section for movement from nested position, shown by the full lines in Fig. 2, to extended position, shown by the full lines in Fig. 3, and the dot and dash lines of Fig. 2.

The stationary section may be of conventional construction having longitudinally and transversely extending frame members 14 and 15 which carry the usual spring supporting struc-

ture and which are connected to legs or uprights 16 spaced inwardly from the transverse members, as shown more clearly in Fig. 4. Pivotedly connected to the front end of the transverse members 15 are hooks 18 normally arranged above the level of cut-out portions or recesses 19 in the legs 16 of the main section. The hooks 18 are disposed to project into openings 20 formed in the legs 16 when the main section is pulled to extended position, thereby limiting its outward movement, as shown in Figs. 3 and 4. The hooks 18 may be swung upwardly so as to disengage the legs 16, thereby permitting the movable section to be pulled away from the stationary section to provide twin beds. If desired, resilient guards 20 (Fig. 4) may be provided on the inner face of the side walls 5 and 6 to prevent the transverse members 15 from binding against the side walls when the two sections are being moved to or from extended position.

The side walls 5 and 6 of the main section are formed with centrally disposed, vertically extending recesses or channels 22 (Fig. 4) and upstanding brackets 23 are firmly secured within the channels 22. The upper ends of the brackets 23 extend above the top of the section and are provided with openings which receive pivot pins 24 for supporting a back rail, designated generally by the numeral 25. As here shown, the back rail consists of a U-shaped member 26 whose ends are bent to provide U-shaped members or side rails 27. Intermediate L-shaped members 28 are integrally joined at their ends to the back and side rails and to the pivot pins 24 adjacent to their bend portions, and a bar 29 is integrally joined at its ends to the legs of the member 26. If desired, the side rails 27 may be provided with the usual arm-rests 30 and the members 26 and 29, constituting a back-rest, and the members 27 and 28, constituting the sides and arm-rest supports, may be chromium plated, enameled or otherwise finished to enhance their appearance.

Laterally projecting lugs or angle irons 32 are secured to the side walls 5 and 6 intermediate the brackets 23 and the rear of the section, these lugs being positioned to support the back-rest in upright position when the structure is used as a couch. The back-rest, arm-rests and associated parts are so constructed and arranged that they may be swung about the pivot pins 24 from the upright position (Figs. 1 and 2) to a position wherein the back-rest proper (parts 26 and 29) is disposed contiguous to the front wall 4, as shown in Fig. 3, thus affording an unobstructed access to the removable section when used either

as a section of a double bed or as one of a pair of twin beds.

When used as a couch the mattresses 9 provide the seat cushions and pillows may be arranged 5 against the back-rest in the usual manner, it being noted that the bars 28 and 29 are positioned to retain the cushions and pillows in place. When the structure is to be used either as a double bed or to provide twin beds, the main 10 or movable section may be easily moved to extended position and the back-rest swung to the position alongside of the front wall, as shown in Fig. 3 and the top mattress 9 may be transferred to the stationary section. It will be noted 15 that when the structure is used either as a double bed or to provide twin beds, the back-rest proper is disposed well below the level of the mattress on the movable section, and hence does not constitute the slightest obstruction to the movable 20 section.

While I have shown and described one desirable embodiment of the invention it should be understood that various changes in shape, proportion and arrangement of parts, as well as the 25 substitution of equivalent elements for those herein shown and described may be made with-

out departing from the spirit and scope of the invention as set forth in the appended claim.

I claim:

A couch bed of the class described comprising inner and outer sections relatively movable from a nested position to an extended position, an up-standing bracket secured to each end of the outer section, the upper end of each bracket extending above the top of the outer section, and a combination back and arm rest comprising an elongate generally U-shaped member having legs whose lower ends extend forwardly substantially at right angles, said forwardly extending ends being bent to provide generally rectangular-shaped arm rests and an intermediate member integrally 15 joined to each of the arm rests, the intermediate members being pivotally secured between their ends to the upper ends of the brackets so as pivotally to support said back and arm rests in a manner such that the back rest may be swung 20 from normal back-supporting position forwardly to a position below the top and contiguous to the front of the outer section, thereby to afford an unobstructed access to said sections when in either nested or extended position. 25

GUSTAVE A. JOHNSON.
